UNITED STATES PATENT OFFICE.

HOWARD GREER, OF CHICAGO, ILLINOIS.

DIE FOR AND METHOD OF MAKING SPIKES.

SPECIFICATION forming part of Letters Patent No. 308,252, dated November 18, 1884.

Application filed December 3, 1883. (No model.)

To all whom it may concern:

Be it known that I, HOWARD GREER, a citizen of the United States, residing at Chicago, county of Cook, State of Illinois, have 5 invented or discovered a new and useful Improvement in Manufacture of Railway-Spikes and Machinery therefor; and I do hereby declare the following to be a full, clear, concise, and exact description thereof, reference being 10 had to the accompanying drawings, making a part of this specification, in which—like letters indicating like parts—

Figure 1 is a front elevation of a machine for cutting and forming spikes, part of the 15 housing being broken away to show the operating mechanism. Fig. 2 is a front elevation of the cutting and forming dies in a closed position, part of the lower die being broken away to show the header. Fig. 3 is a trans- 20 verse vertical section on the line xx , Fig. 1. Fig. 4 is a similar section on the line yy , Fig. 2. Fig. 5 is a perspective view of the working face of the lower die. Fig. 6 is a perspective view of the spike-blank. Fig. 7 is 25 a perspective view of the completed spike.

My invention relates to certain improvements in the manufacture of spikes such as are employed in securing the rails of railway-tracks, in which I propose to use, by 30 preference, Bessemer or open-hearth steel or steel rails, or the cross ends thereof, though iron may be employed, if so desired; but the granular structure of the steel enables it to be employed more advantageously, since in 35 the absence of fiber the direction of the line of cut is immaterial, and hence I will describe my invention with particular relation to the use of steel therein.

In working the present invention I first 40 produce by ordinary methods of rolling a bar or blank approximately of the shape in cross-section of the spike to be made, a perspective view of such blank or bar being represented at A. The central part, b , is about the thick- 45 ness of one side of the spike-shank when completed, and a rib, a , is made along one side of one edge of the blank, and the opposite edge is beveled, as represented at e ; but the metal is so rolled that in the part a , which 50 goes to form the spike-head, enough metal is there secured to form the ears s , as also the

rearward lip, s' , such as are usually found in spike-heads; and preferably this excess metal is so disposed, as represented at a' , that it shall be wholly in line with the shank b , so 55 that when an endwise force is applied by means of the header H the entire force of the latter will be operative on such excess a' , and will not tend to any material extent to bend or distort the metal of the rib a , from which 60 the overlapping lip s' of the spike is made. This blank is to be cut up by transverse parallel cuts into a series of blanks, and the head part a is to be upset slightly, so that 65 the extra or surplus metal therein may be swaged out to form the ears s and the back lip, s' . To do this work I employ a pair of dies, B B' , and a header, H . The upper die, B , is secured to a plunger or die-carrier, D , mounted in a housing, D' , and is recipro- 70 cated by an eccentric, d , secured to a power-shaft, d' . This die has a form of face corresponding in shape to that of the upper side of the blank or to the headed side of the spike. The lower die, secured to the founda- 75 tion or bed of the machine, has a face corresponding in shape to that of the lower side of the blank A.

The header H is suitably arranged to reciprocate back and forth beneath the working-face of the upper die and back of the lower die, and it receives a reciprocating motion by means of a suitable connection with the driving mechanism, such as shown, where the header is attached to the arm p' 80 of the rock-shaft p , the other arm, p^2 , of the rock-shaft being attached to the connecting-rod o of the eccentric d^2 , secured to the power-shaft d' . The width of the working-face 85 of the upper die is equal to the width of the spike-blank to be cut off, and beneath this face is a vertical wall, g , which acts as a stop in the feeding of the blank. In this vertical wall, and immediately opposite the headed end of the spike-blank when fed there- 90 in, is a groove, g' , in the proper position and of suitable length and depth for the forming therein of one of the ears s of the spike-head. On the inside of the lower die is a ledge, r , of 95 proper length and shape and position, so that 100 after a blank is cut by the downward stroke of the upper die its shank and point will be

gripped between such ledge and the working-face of the upper die. In the inner wall of the lower die a slight recess, r' , is made immediately opposite the groove g' , and the end of the ledge r is also rounded off at the same point. In this recess the other ear s is made, and over the rounded corner of the ledge r the back lip, s' , is made. The formation of these ears and lip is effected by the forward stroke 10 of the header H , which is caused to advance as the upper die, B , comes into gripping position, so that by the action of the header on the part a' of the blank the excess of metal in such part a will be caused to flow out laterally 15 into the grooves g', r' and into the cavity formed by the rounded corner of the ledge, and thereby form the ears s and the back lip, s' .

In so far as relates to the form or forms of the blank herein shown and described, the 20 same is not claimed, but will form the subject-matter of an application to be filed in due time.

In application No. 113,386, filed December 3, 1883, I have described and claimed a machine for forming lateral ears on a spike-head by means of the compressive action of a die moving at right angles to the body of the spike; but in the machine described and claimed herein the lateral ears are swaged out 25 by a heading-die moving in a plane parallel with the length of the spike.

I claim herein as my invention—

1. The die B , provided with the vertical

wall g , having therein the groove g' , opposite the head of the blank and on one side thereof, 35 in combination with the die B' , provided with the recess r' opposite the head portion of the blank, but on the other side thereof, and the header H , substantially as set forth.

2. The die B , provided with the vertical 40 wall g , having therein the groove g' opposite the head of the blank and on one side thereof, in combination with the die B' , having the recess r' opposite the head of the blank, but on the opposite side thereof, and having also the 45 ledge r cut away opposite the groove r' , and the header H , substantially as set forth.

3. The herein-described method of manufacturing spikes, which consists in forging or rolling a blank to approximately the size and 50 shape in cross-section of the finished spike, but with an excess of metal, as at a' , on the head-forming edge thereof, outside the plane of finish of the spike-head, cutting spike-blanks from said blanks by a series of parallel 55 cuts in dies adapted to cut and grasp the spike-blank, and then expanding or expressing laterally out such excess of metal while the blank is held between the cutting-dies by a suitable header, substantially as set forth.

In testimony whereof I have hereunto set my hand.

HOWARD GREER.
